(57) **CLAIM**

The ornamental design for a probe for an ultrasonic diagnosis apparatus, as shown and described.

DESCRIPTION

FIG. 1 is a first perspective view of a probe for an ultrasonic diagnosis apparatus showing my new design;

FIG. 2 is a second perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines and areas within them depict portions of the probe for an ultrasonic diagnosis apparatus that form no part of the claimed design.

1 Claim, 4 Drawing Sheets
